FIG. 6.

FIG. 7.

FIG. 5

FIG. 2

FIG. 3

FIG. 4

Walter L. Fairchild, ^{INVENTOR}
Charles T. Wilson, ^{BY} ATTORNEY.

UNITED STATES PATENT OFFICE.

WALTER L. FAIRCHILD, OF NEW YORK, N. Y.

PNEUMATIC TUBE.

Application filed June 28, 1921. Serial No. 481,059.

This invention relates to a new and improved pneumatic tube, and while the invention is applicable to pneumatic tubes adapted for a variety of uses, it particularly relates to the endless inner tubes commonly employed in the casings of pneumatically tired vehicles.

The invention disclosed in this application in some of its aspects is a continuation in part of my application filed September 3, 1920, Serial No. 408,016.

One of the objects of the invention is to provide a new and improved pneumatic tube wherein the entire tube, including the part wherein the ends of the tubular structure are united, and the part through which the valve stem extends, possesses a degree of homogeneity hitherto unattained in pneumatic tubes.

Another object of the invention is to provide a pneumatic tube of the above character, wherein that portion of the tube through which the valve stem extends, is so strengthened and reinforced, that any possibility of leaks occurring between the metal and the encircling rubber wall of the tube are practically eliminated.

Another object of the invention is to provide a tube wherein the mounting of the valve stem is such that the usual strain exerted upon this element will not tear or loosen it from its mounting in the tube, the said mounting comprising a reinforced homogeneous wall, through which the valve stem extends.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawing, wherein I have shown a preferred form of embodiment of my invention:

Figure 1 is a sectional view taken through a pneumatic tube in the neighborhood of the valve stem, the latter being shown in side elevation.

Figure 2 is a transverse sectional view taken through my improved tube, showing a portion of the valve stem in side elevation.

Figure 3 is a top plan view of the structure shown in Figure 1.

Figure 4 is a detail view in perspective of one end of the tube, showing the reinforcing means employed for the anchorage of the valve stem;

Figure 5 is a view similar to Figure 4, but showing a slightly modified form of construction.

Figure 6 is a detail view, similar to Figure 1, but showing the parts after vulcanization.

Referring now to the drawing, wherein similar reference characters refer to similar parts throughout the several views thereof, the reference numeral 1 illustrates one end of the tube, and 2 the opposite end thereof, which ends are fastened together to form a continuous tubular structure.

At this point it may be noted that the material of the tube before the ends thereof are united, is preferably composed of raw rubber, that is to say, rubber in the same condition it was when discharged from a forming mold, said rubber containing the proper ingredient commonly employed in the production of such tubes, so that when the vulcanizing operation is effected, the material is reduced to its finished state.

The reference numeral 3 denotes a ring which is also preferably composed of raw rubber, and 4 denotes what I term a "base patch," the latter being preferably of oblong, curved form, and composed of a fabric such as canvas, both sides of which have been rubberized, that is to say, coated with a layer of raw rubber of the same consistency as that of the inner tube.

In the preferred form of embodiment of my invention, this base patch 4 is preferably located between the ring 3 and the united ends 1 and 2 of the tube, as clearly shown in Figure 1 of the drawing.

The reference numeral 5 indicates a patch, preferably located exteriorly of the united ends 1 and 2 of the tube, said last named patch being also of oblong curved form and preferably composed of rubberized canvas, such as has been described in connection with the base patch 4.

The pneumatic tube is provided near its end with an aperture 6, through which the valve stem 7 extends. This valve stem is provided with a head or flange 8, which normally lies in engagement with the inner

105

110

115

surface of the ring 3, and a reduced neck portion 9, which extends through apertures provided in the ring 3, the base patch 4, the aforesaid aperture 6 of the pneumatic tube, and the exterior patch 5.

Mounted upon the threaded portion of the valve stem 7 is a nut 10, which is adapted to be screwed downwardly upon said stem, until it engages with the outer surface of 10 the patch 5, whereby this latter element, the end 1 of the pneumatic tube, the base patch 4, and the ring 3 are tightly clamped between said nut and the upper face of the flange or head 8.

15 The end 2 of the pneumatic tube is inserted between the base patch 4 and the exterior patch 5, so that preferably it slightly overlaps one end of the ring 3, said end 2 and the end 1 of the pneumatic tube 20 lying in abutting relation, as indicated by the dotted line 11—11 of Figures 1 and 3.

Having now described the construction, and the relation of the elements constituting my improved pneumatic tube, I shall now 25 proceed to describe the operation of assembling or uniting said parts.

This operation is substantially as follows: The operator having provided himself with one of the base patches 4, and a ring 3, inserts a valve stem through the openings provided in said elements, and the valve stem is then inserted through the opening provided in the end of the tube 1. This operation, of course, carries the ring and the 35 base patch inside the end of the tube 1. The operator then kneads the ring and tube so that the engaging surfaces of said tube, ring, and the interposed base patch will be united by cohesion. The base patch 5 is 40 next positioned exteriorly of the end 1, and the parts again kneaded, whereby the engaging surfaces of said last named base patch and the tube are united by cohesion.

It is, of course, apparent that all the above 45 described parts may be assembled, and all the engaging surfaces caused to cohere by a single kneading operation. When the above parts have been so assembled, and caused to cohere, the nut 10 of the valve 50 stem is screwed home, whereby all the parts are firmly clamped together.

Figure 4 illustrates the end 1 of the tube with the last mentioned assembly.

The end 2 of the tube is next inserted 55 between the patches 4 and 5 until its end abuts the end 1 of the tube. When this has been done, the assembled parts are again kneaded, so that the end 2 of the tube is firmly united by cohesion to the end 1 of 60 the tube, and the rubberized surfaces of the patches 4 and 5.

It will be understood, of course, that before the ends of the tube have been brought together, as shown, the operator has sprinkled some talc, or similar powdered mate-

rial, into the tube to prevent the opposed surfaces not intended to be united from being united during the kneading operation.

When these operations have been effected, the tube is ready for vulcanization, and 70 when this operation has been performed, the entire rubber and canvas structure in the vicinity of the valve stem, forms a homogeneous wall, through which the metallic neck 9 of the valve stem extends, the layers 75 being firmly vulcanized about the aforesaid neck.

In the drawing the various layers of material in the vicinity of the valve stem have been illustrated as being separate elements. 80 It will be understood that this illustration is intended to illustrate these parts before vulcanizing, the line separating them being in the interest of clearness of illustration, rather than an accurate illustration of the 85 aforesaid parts as they appear in the finished tube.

It will accordingly be seen that I have provided a construction well adapted to attain, among others, all the ends and objects 90 above pointed out, in an exceedingly efficient manner. The ends of the tube are firmly joined together, and held in such condition by the reinforcing means, that that part of the tube adjacent the valve stem is anchored 95 and reinforced not only by the ring 3, but by the exterior and interior patches, which co-operate with said ring 3 to provide a firm anchoring for said valve stem, and provide a firm mechanical support for the latter. 100

In Figure 5 of the drawing I have shown a slightly modified form of construction, in that the base patch 4 instead of being positioned between the ring 3 and the abutting ends of the tube, is positioned interiorly of 105 the aforesaid ring, and is firmly united to the inner surface of said ring, and to the neighboring parts of the ends 1 and 2 of the tube. This structure is shown in my aforesaid pending application. 110

It will be understood that various changes may be resorted to in the form, construction and arrangement of the several parts without departing from the spirit and scope of my invention, and hence I do not intend to be limited to the details herein shown and described except as they may be included in the claims. 115

Having thus described my invention what I claim as new and desire to secure by Letters Patent is:

1. An inner tube for pneumatic vehicle tires having a combined joint and valve structure comprising, a ring of rubber located within the tube and overlapping the joint, a strip of rubberized material overlapping said ring and joint, and a valve piercing the ring, the strip and the tube, the said ring, strip and joint being vulcanized 125 into a substantially homogeneous condition. 130

2. An inner tube for pneumatic vehicle tube, and a valve piercing the ring, the tires having a combined joint and valve strips and the tube, the said ring, strips structure comprising, a ring of rubber located within the tube and overlapping the 10 joint being vulcanized into a substantially homogeneous condition.
- 5 joint, a pair of strips of rubberized material overlapping said ring and joint, one of said strips being within and one without the

In testimony whereof, I affix my signature.

WALTER L. FAIRCHILD.
